No. 36,851.

Patented March 15, 1904.

UNITED STATES PATENT OFFICE.

FELIPPE A. BROADBENT, OF BALTIMORE, MARYLAND.

DESIGN FOR A MANTEL.

SPECIFICATION forming part of Design No. 36,851, dated March 15, 1904.

Application filed January 22, 1904. Serial No. 190,243. Term of patent 7 years.

To all whom it may concern:

Be it known that I, FELIPPE A. BROADBENT, a citizen of the United States, and a resident of Baltimore, Maryland, have invented a new, 5 original, and ornamental Design for Mantels, of which the following is a specification, reference being had to the accompanying drawing, forming part thereof.

In the drawing I have illustrated the design 10 in a front elevation.

What I claim as new is—

The ornamental design for a mantel as herein shown.

FELIPPE A. BROADBENT.
